UNITED STATES PATENT OFFICE.

AARON H. WOLFF, OF NEW YORK, N. Y., ASSIGNOR TO THE WOLFF GAS RADIATOR MANUFACTURING COMPANY, OF SAME PLACE.

DESIGN FOR A GAS-STOVE.

SPECIFICATION forming part of Design No. 26,327, dated November 24, 1896.

Application filed August 29, 1896. Serial No. 604,333. Term of patent 7 years.

To all whom it may concern:

Be it known that I, AARON H. WOLFF, a citizen of the United States, residing at New York, in the county and State of New York, 5 have invented a new Design for Gas-Stoves, of which the following is a specification.

The leading features of my design consist in the open-work diamond configurations, leaflet and branch ornaments, and scallops of the 10 base, the scroll and open-work ornaments of the hanging face-plate, and the leaflet ornaments and scallops of the top plate.

In the drawings, Figure 1 is a front elevation, and Fig. 2 is an end view.

15 The design of the ornamental base *c* comprises open-work diamond configuration formed by the intersecting bars 7, the surface leaflet and branch ornaments 8, and the ornamental scallops 6 at the lower edge, and the ornamental feet.

The design of the hanging face-plate *b* comprises the scroll ornaments 4 and intermediate openings 5. The top plate *a* has an outward and downward curved edge, and the 25 design of the said top plate comprises the

edge scallops 2, of corresponding configuration to the scallops 6 of the base *c*, and the leaflet ornaments 3. The ordinary pipes of a gas-stove intervene between the base and top frame and plate, and their ornamentation 30 is not material.

What I claim is--

1. The design for a gas-stove as herein described and shown in the accompanying drawings.

2. In a design for a gas-stove, the base as herein described and shown in the accompanying drawings.

3. In a design for a gas-stove, the hanging face-plate as herein described and shown in 40 the accompanying drawings.

4. In a design for a gas-stove, the top plate as herein described and shown in the accompanying drawings.

Signed by me this 28th day of August, 1896. 45

AARON H. WOLFF.
